JOHN R. ROSE AND EDWARD L. CALEY, OF PHILADELPHIA, PENNSYLVANIA,
ASSIGNORS TO COX, WHITEMAN & COX, OF SAME PLACE.

Design No. 2,612, dated April 9, 1867; antedated March 12, 1867.

DESIGN FOR THE PLATES OF A COOK'S STOVE.

The Schedule referred to in these Letters Patent and making part of the same.

TO ALL WHOM IT MAY CONCERN:

Be it known that we, J. R. ROSE and E. L. CALEY, of the city of Philadelphia, in the State of Pennsylvania, have invented or produced a new and original Design for the Plates of a Cook's Stove, which we term "The Quaker City;" and we do hereby declare that the following is a full, clear, and exact description of the same, reference being had to the accompanying drawings, making a part of this specification, and to the letters of reference marked thereon.

The nature of our design consists, as hereinafter described and shown, in the form of the edge mouldings and face sides of the door plates of the right and the left sides of the stove, and in the form and arrangement of three raised or bas-relief tablets near the bottom edge of each of the said right and left plates. In the drawings—

Figure 1 is a perspective view of the said cook's stove, showing the whole of one of the two sides of the same.

Figure 2, a transverse section of one of the edges and part of the faces of the door-plates A B C; and

Figure 3, a transverse section of the edges and front of the faces of the raised tablets D E F on the right and the left side-plates of the stove.

Each of the door-plates A B C has its edges and face side made in the form shown in figs. 1 and 2. Each of the three tablets C D E consists of an oblong raised portion, having straight sides and circular ends, and having a boundary edge, the cross section of which, in connection with the plate, is formed as shown in the drawings, figs. 1 and 3.

We do not desire to include the ornamental figure α in the centre of the door-plates; but what we claim as our invention, and desire to secure by Letters Patent, is—

The design herein specified and shown for the doors and side-plates of a cook's stove.

JOHN R. ROSE,
EDWD. L. CALEY.
